Primary Examiner—Bernard Ansher**Assistant Examiner—**Mitchell I. Siegel**[57] CLAIM**

The ornamental design for a bottle of cyanoacrylate adhesive, as shown and described.

DESCRIPTION

FIG. 1 is a perspective view of a bottle of cyanoacrylate adhesive showing my new design;

FIG. 2 is a exploded perspective view thereof;

FIG. 3 is a right side elevational view of FIG. 1;

FIG. 4 is a front elevational view of FIG. 1;

FIG. 5 is a left side elevational view of FIG. 1;

FIG. 6 is a rear elevational view of FIG. 1;

FIG. 7 is a top plan view of FIG. 1 and,

FIG. 8 is a bottom plan view of FIG. 1.

FIG. 1

FIG. 2

FIG. 3
